UNITED STATES PATENT OFFICE.

MATTHIAS BROCK, OF BOSTON, MASSACHUSETTS, ASSIGNOR TO UNITED SHOE MACHINERY CORPORATION, OF PATERSON, NEW JERSEY, A CORPORATION OF NEW JERSEY.

SHAPING-MACHINE FOR SHOES.

1,376,388.

Specification of Letters Patent. Patented Apr. 26, 1921.

Application filed May 21, 1918. Serial No. 235,814.

To all whom it may concern:

Be it known that I, MATTHIAS BROCK, a citizen of the United States, residing at Boston, in the county of Suffolk and State 5 of Massachusetts, have invented certain Improvements in Shaping-Machines for Shoes, of which the following description, in connection with the accompanying drawings, is a specification, like reference characters 10 on the drawings indicating like parts in the several figures.

This invention relates to machines for shaping upper materials and is herein shown as embodied in a machine for molding 15 the heel portions of shoe uppers of the type shown substantially in prior United States Patents, Nos. 1,197,437 and 1,197,439, granted Sept. 5, 1916 upon applications filed by me and in my copending application Serial No. 172,683, filed June 4, 1917.

An object of the invention is to produce a molding mechanism organized to mold the end of a shoe upper to a shoe end form and over the margin of the bottom or tread 25 face of the form to produce a flange upstanding at a definite angle relatively to the tread face and located a predetermined distance inwardly from the edge of said tread face. The ends of shoe uppers so molded 30 are particularly adapted for sewing around the ends of the shoes, the upstanding flange forming a sewing flange which is attached to the sewing rib of the insole. The invention is applicable to both the heel and toe 35 ends of shoes, there being certain types of shoes having sewed heel seats, such, for example, as "powder mill" shoes, in which the upper is sewed to a rib extending entirely around the insole. A further object 40 of the invention is to produce improved constructions of molding and shaping instrumentalities and associated mechanisms as will be later pointed out.

An important feature of this invention, 45 therefore, consists in a novel organization of shaping instrumentalities coöperating to shape the shoe upper to a shoe end form with the marginal portion of the upper extended inwardly over the tread face of the 50 form a predetermined distance from the edge of the tread face and formed with an upstanding flange extending at a definite angle with relation to said tread face and located a predetermined distance inwardly

from the edge of said face. A further feature consists in a novel construction and arrangement of flange forming means. In the illustrative embodiment of the invention, the shaping of the marginal portion of the upper is effected by confining the margin between advancing and closing wipers and a flange forming block of permanent contour whose edge face extends at a definite angle to the tread face of the form and engages the inner side of the upstanding margin of the upper, this block being mounted on and guided by the tread face of the form for movement by the advancing wipers a predetermined distance longitudinally of the form, which distance may 70 correspond to the distance it is desired to locate the upstanding flange from the edge of the form. The contour of the flange forming block will correspond to the contour of the desired flange and successive 75 advances of the end wipers will shape the margin of the upper to the edge face of the block so that the flange will upstand from the tread face at the angle determined by the angular relation of the edge face of the 80 block to the tread face of the form.

These and other features of the invention including a novel arrangement of end embracing and clamping mechanism, and improved constructions in wiper and wiper 85 controlling mechanisms, will be more fully pointed out in the detailed specification following and are illustrated in the accompanying drawings.

In the drawings,

Figure 1 is a view in side elevation of a machine embodying the invention, a portion of the frame being broken away to disclose interior mechanism.

Fig. 2 is a top plan view of the end embracing mold and its operating mechanism,

Fig. 3 is a perspective view of the embracing band or mold and its backing, detached,

Fig. 4 is a plan view of the wiper mechanism,

Fig. 5 is a detail view in perspective illustrating the formation of the flange at the margin of the upper.

As pointed out in said prior patents, the machine comprises a plurality of duplicate units built into one machine so that a plurality of shoe uppers may be in process at

the same time. It will suffice to describe the present invention as applied to one of said units.

The upper shaping mechanism comprises a last or form 2, herein shown as a metal heel form of more pronounced curvatures than the corresponding last; a multi-part form embracing mold, Figs. 1, 2 and 3, backwardly into which the form carries the 10 work; and heel embracing wipers, Figs. 4 and 5, comprising advancing and closing end members 5 and side members 6 that have closing movement without advancing.

The machine is power driven, being controlled by a foot treadle 10 connected with a clutch 12 on a driving shaft 13. This shaft is geared to the cam shaft 14 which operates through a lever 15, a rod 16, and form carrier 18 to draw the form back into the mold; 20 through a lever 20 and toggle 22 to close the mold for clamping the upper about the side faces of the form; through certain novel connections later to be described to close the wiper controlling clutch and set the wipers 25 to reciprocating; and through a lever 26, toggle 27, and rods 30, 32 and spring 33 to raise the form yieldingly against the wipers. These movements having been effected, the cam shaft 14 comes automatically to rest 30 while the wipers, which are driven from a continuously running pulley 35, are continued in reciprocation to shape the marginal portion of the upper to the margin of the tread face of the form 2 and to form the 35 upstanding marginal flange as later described, by repeated rubbing movements back and forth over the marginal portion of said tread face. The operator uses his judgment as to the length of time during which 40 the work should be subjected to the action of the shaping instrumentalities and then again depresses the treadle 10. This results in the rotation of cam shaft 14 to cause opening of the wiper clutch and unjacking of the 45 shoe and restores all of the upper shaping instrumentalities to their starting positions, returning the inside form 2 to the position shown in Fig. 1 preparatory to the removal of the shaped upper therefrom and the application of an unshaped upper to the form. 50

The operating mechanism and organization thus far described is like that more fully shown and described in said prior patents and copending application, except as 55 noted, and the present invention, except as expressly stated hereinafter, is not concerned with the detailed construction thereof.

To mold the marginal portion of the upper into an upstanding flange, the bottom face 60 of the inside form 2 which corresponds to the tread face of the last or shoe, is recessed as shown in Fig. 2 to provide a slideway in which the base of a flange forming plate 34 is dovetailed and guided for movement longitudinally of the form and shoe end. This

plate has a permanent edge contour similar to the contour of the margin of the tread or bottom face of inside form 2 and conforming to the desired contour of the upstanding flange which is to be formed at the margin 70 of the upper. The edge face of the plate extends at a definite angle, preferably substantially perpendicularly, to the plane of the bottom face of the form. This plate is formed with an elongated vertical slot 36 75 therein through which a stud 38 (Fig. 5) extends and threads into a bore 37 (Fig. 2) in the bottom face of the form. This stud in coöperation with the end wall of the slot limits and also determines the extent to 80 which the block 34 may be moved lengthwise relatively to the edge of the form end by the advance of the end embracing wipers.

This flange forming plate, which also acts as margin holding means confining the upper against the edges of the wipers as they advance and close and restraining the marginal stock from doubling on itself to produce folds similarly to the deformable member of my copending application aforesaid, 90 is maintained normally in rearwardly projected position in the slideway on form 2 with its end edge aligned with or adjacent to the end edge of the form, according to adjustment, by means of the presser member 95 50 constituting the upper arm of a bell crank lever fulcrumed in the form carrier 18 and having its lower and horizontal arm 52 pressed downwardly by a spring plunger 54 (Fig. 1). When the carrier 18 with its inside form 2 is drawn backwardly to draw the form back into the mold, the first advance of the wipers will move the flange plate 34 longitudinally of the form 2, swinging the bell crank lever 50, 52 and riding the reduced end of arm 52 up into the notch in a latch finger 60 vertically adjustable in a clamping block on a spring pressed latch holding member 62 pivotally mounted on an arm 63 which is hung intermediate of its 105 ends on a spindle carried by the machine frame and held against an abutment at its lower end by a set screw engaging a rib on the frame at its upper end. The finger 60 may be vertically adjusted to coöperate properly with the bell crank lever arm according to the movement given said arm by the advance of the wipers, the extent of which movement may vary in different cases. This latch will engage and hold the bell crank 110 lever until the carrier 18 is moved forwardly to unjack the shoe at the end of the shaping operation. The upper end 50 of the lever cannot be swung back by the spring plunger 54, and the flange forming plate 34 will remain in the position to which it is moved by the first advance of the wipers, until the end of the shaping operation when the carrier moves forwardly, disengaging the lever from the latch 60 and permitting spring plunger 115 120 125 130 135

54 to return the flanging plate to its initial position.

Preferably, I employ a connection between the presser arm 50 of the bell crank lever 5 and the flange forming plate which may be adjusted to vary the extent to which the plate is projected relatively to the end edge of the form at the beginning of the operation. Such a connection is shown in the set screw 10 39 entering through a bore in the end of plate 34 and coöperating with the presser bar 50 and stud 38 adjustably to determine the initial position of the flange plate on the form and relatively to its rear edge. By 15 this adjustment, the flange plate may be made to project beyond the rear edge of the form to permit the upper to be pressed against it in such manner as to hold up the "wings" or ends of stiffener material so that they may be molded 20 properly over the tread face of the form with the upper by the wipers. There is a tendency when the upper is clamped to the sides of a shoe end form, or when the wipers 25 engage the upper, or the upper and end stiffener when used, for the stock to tip about the rear end of the form and to pull the side portions down, leaving an insufficient width of margin to bend in and flange 30 and such an adjustment is advantageous when molding shoe uppers and uppers provided with unmolded stiffeners. When molded stiffeners are used, the end edge of the plate may be substantially alined with 35 the end edge of the form. These and other positions of adjustment may be secured through the set screw 39.

It will be evident from the preceding description that at the start of the operation, 40 the rear end of the edge of the flange forming plate 34 will be adjacent to or near the edge of the form tread face at its rear extremity as seen in Fig. 1, this position being determined by previous adjustment of set 45 screw 39 in accordance with the nature of the work. The marginal portion of the shoe upper or upper and end stiffener will stand up around the curved rear end and sides of the shoe end form, and as the end wipers are 50 advanced and closed these portions of the stock are maintained against the edges of the wipers and restrained from downward displacement. The wipers will be advanced over the face of the form, progressively flattening down the upper materials over and 55 parallel to the bottom or tread face of the form until they have displaced the flanging plate 34 to the limit determined by the stud 38. The plate will then remain in this position through the engagement of arm 52 and 60 latch 60 as previously described, and as the wipers are repeatedly advanced and retracted, the margin of the upper will be molded to the bottom face of the form and 65 inwardly of the edge of the form to the edge

face of the flanging plate against which edge face it will be shaped to upstand from the bottom face of the form substantially at the angle predetermined by the angular relation of said edge face to the plane of said bottom 70 face.

When, in the operator's judgment, the upper has been properly molded and flanged, the reciprocation of the wipers is discontinued and the shoe unjacked as previously de- 75 scribed.

Preferably, the wipers are started in operation coincidently with the closing of the outer mold on the form 2, and accordingly, in the illustrated machine, I have connected 80 the end of the wiper-clutch controlling arm 66 with the outer mold closing toggle 22 by a second toggle 68 one of whose links carries a pin 69 which projects into a slot in the other link, the pin being engaged by the 85 hooked end of one arm of a bell crank lever 70 normally held in engagement with said pin by a spring connected to its other arm. This bell crank lever is carried by the forward end of the toggle 22 so that when the 90 mold closing toggle 22 is straightened to close the mold, the bell crank hook will flex the wiper controlling toggle 68 to pull up the wiper-clutch controlling latch 66 and start the operation of the wipers, the latch being 95 subsequently tripped by depression of the member 70 as will be hereinafter described. When the toggle 22 is flexed at the end of the shaping operation to open the outer mold, the member 70 is returned to the position shown in Fig. 1.

The wiper mechanism herein shown, like the mechanism illustrated in said prior patents, comprises carrier plates 4 connected to pivot pins 7 on links 9 which extend forwardly from a cross-bar 11 on a wiper operating rod 17, the carrier plates having curved outer edges in bearing engagement with the walls of the recess in the wiper head in which the wipers are mounted. 105 Rolls 55 on normally stationary studs 58 serve by engagement with the walls of slots 51 in the carrier plates to cause the plates to be swung inwardly and outwardly during the advancing and retracting movements imparted to them by their operating connections. The end wiper plates 5, which are constructed to operate upon the work around the curved rear end of the form, are fast 110 on the carrier plates 4 and are jointed together to swing with the carrier plates about an axis close to their wiping edges and substantially midway between the opposite sides of the mechanism. The side wiper plates 6 hereinbefore mentioned are ar- 115 ranged to operate as extensions of the end plates 5 along the opposite sides of the form, the wiping edges of all the plates lying in the same plane. As in the constructions shown in the prior patents, it is contem- 120 125 130 135

plated that the side plates 6 shall be closed inward laterally of the form without any substantial advancing movement lengthwise of the form, and to this end the plates 6 have dovetailed ribs slidable in guideways in the lower faces of the carrier plates 4 and carry pins 61 which project upwardly through slots 53 in the carrier plates, these pins being controlled by means to be herein-
10 after described in such manner as to restrain the plates 6 substantially from lengthwise movement while permitting them to be swung laterally of the form. It will be evident that in the operation of this mech-
15 anism the advancing movement of the cross bar 11 and the links 9 will move the carrier plates 4 and the end wipers 5 bodily lengthwise of the form in sliding engagement with the side wipers 6 which are re-
20 strained from lengthwise movement, and that the rolls 55 in the slots 51 will cause the carrier plates 4 to be swung simultaneously inward, carrying with them both the end wipers 5 and the side wipers 6. In
25 order to make a close joint between the members 5 and 6, the members 6 are recessed slightly on their inner edges, as shown in Fig. 4, to provide straight slideways for engagement with the members 5, these slide-
30 ways terminating in shoulders 19 at the rear extremities of the formed edges of the members 6 and the arrangement being such that at the end of the advancing and closing movement of the wipers the ends of the
35 members 5 are substantially in engagement with the shoulders 19, thus avoiding any substantial break in the regular continuity of the formed wiper edges such as might produce an irregularity on the surface of the
40 upper.

It is important to the successful operation of the upper flanging means that the wipers at the limit of their movement shall embrace the flanging plate 34 in substantially close relation to the edge of the plate along the sides as well as around the rear end, with due allowance of course for the thickness of the upper materials. The construction shown provides for adjustment of the
45 wipers to insure their location in effective co-operative relation to the flanging plate. Adjustment of the carrier plates 4 and the end wipers 5 bodily lengthwise of the form may be effected by the adjustable connec-
50 tion between the rod 17 and its operating means, as in former constructions such as shown in Patent No. 1,197,439. A compensating adjustment of the carrier plates to determine the proper limit of inward swing-
55 ing movement of the wipers is effected by movement of the rolls 55 lengthwise of the form, these rolls having threaded studs 58 projecting through slots 59 in the cover plate 75 and carrying clamping nuts 76.
60 In order, for example, to cause the wipers
65

to close farther inwardly, the rolls 55 would be moved outward along the slots 59, thus causing the carrier plates to swing about their connections with the links 9 in a direction to force the wipers inwardly, such movement of the carrier plates being permitted by the provision for outward swinging movement of the links 9. By reason of the manner in which the wipers are mounted and controlled, adjustment to position the different portions of their edges at uniform distances from the edge of the plate 34 usually necessitates proportional movements of the rod 17 and of the rolls 55. It will be evident, moreover, that by relative adjustment of the rolls 55 in their slots the limits of inward movement of the wipers at the opposite sides of the plate 34 may to some extent be varied relatively.

As above stated, it is desirable that at the limit of closing movement of the wipers the ends of the plates 5 be positioned close to the shoulders 19 of the plates 6 in order to avoid any substantial break in the regular continuity of the wiper edges. To provide for this condition, notwithstanding variations in adjustment of the wipers, the pins 61 in the construction herein shown are connected by links 57 to the studs 58 of the rolls 55. It will be evident that these links serve the purpose of the transverse guide slots heretofore provided to restrain the pins 61 and the side wiper plates from substantial movement lengthwise of the form, and each link serves additionally, upon adjusting movement of its roll 55, to effect a corresponding compensating adjustment of the connected side wiper plate 6. Obviously, with the wiper plates 6 held against lengthwise movement, swinging movement of the carrier plates 4 effected by adjusting the rolls 55 as above explained would slide the wiper plates 5 along the plates 6 in one direction or the other and thus vary the ultimate relation between these plates at the limit of closing movement of the wipers. By the connections 57, however, movement of the side plates 6 is effected in the proper direction to compensate for this tendency and to insure proper continuity of the wiper edges when the wipers are closed.

In shaping or molding the upper to the sides of a shoe end form, particularly at the heel end, as described and illustrated, it is necessary to successful shaping that the upper be closely molded to the sides of the form at the front end, and particularly at that incurved side of the form corresponding to the inner side of the human foot. Accordingly, my invention includes an outer molding mechanism organized closely to mold the upper to the side faces of the shoe end form and to apply with equal facility forcible molding pressure to the front portion of a heel end form at each side of the

form. This molding mechanism comprises a substantially U-shaped end embracing band having a backing of articulated construction in the form of a series of interconnected links, to the inner face of which a lining member is attached, as shown in Figs. 2 and 3 and in said prior patents. This molding member is supported in the head of the machine frame and is closed upon the heel end form by a plunger 80 operated through the toggle 22 and having a pin and slot limited yielding connection with the rear end of the mold, and carrying also a cross bar 82 from the opposite ends of which extend forwardly links 84 coöperating with certain devices to apply molding pressure to the end, corners, and sides of the mold. Segmental blocks 86 are mounted to slide in arc shaped guideways formed in the head of the machine and carry spring pressed plungers which engage the faces of the mold links at the rear end and corners of the end of the mold. These blocks are moved in their guideways to apply pressure to said parts of the mold through a pin connection with the links 84, the forward ends of which are designed to apply pressure to the sides of the mold at the front end of the heel end form 2. The parts so far described are shown in said prior patents and need not be further described here. I have, however, with the objects previously mentioned, improved the prior constructions of heel mold by providing for powerful pressure against the opposite sides of the mold in the region of the front end of the shoe form. To this end, the forward portions of the articulated backing of the mold which, as previously constructed, are recessed, forming upper and lower ears, are provided with pressure blocks 85 hinged to the backing members rearwardly toward the heel end of the form and having at their forward ends spring pressed plungers 87 to engage the sides of the mold at its front end. These blocks 85 have their outer faces beveled to form wedge surfaces 851 with which rolls 852 on the forward ends of the links 84 coöperate to exert powerful yielding pressure against the forward end of the mold. The blocks 85 are guided between the ears at the opposite sides of the mold and preferably are further guided by upper rolls 853 (Fig. 2) which ride over the upper faces of the blocks.

When the toggle 22 is operated to move the plunger 80 forwardly, therefore, the front end of the mold presses the upper against the front portion of the shoe form with powerful yielding pressure and strong yielding pressure is applied through the backing to the upper at the corners and sides of the heel. It is desirable, owing to the strong closing pressure applied to the blocks 85, positively to retract the opposite side portions of the mold at the front end when

the shoe is unjacked, and accordingly bell crank levers 854 journaled in the machine head are connected at the ends of their forward arms to pins 88 on the mold by links shown in dotted lines in Fig. 2 and have their short arms located in the plane of third rolls 855 carried at the ends of the links 84 so that when said links are retracted through the toggle 22 and plunger 80, said rolls 855 will strike the bell cranks 854 and through the described link connections positively swing the side portions of the mold outwardly.

The wedge faces 851 of the blocks 85 in combination with the yielding plungers acting against the ends of the mold backing insure shaping of the upper to the incurved side face of an end form for the heel end of the shoe, such as the form 2, illustrated herein, the pressure plunger carried by the block 85 yielding substantially more at the full or fuller outer side face of the heel end form than at the inner side face, so that the described mechanism may be used with equal facility for right and left lasts or right and left heel end forms for shoes.

In order to avoid the possibility of distortion of the molded upper materials by tendency of the wipers to strip them from the form, it is desirable to stop the operation of the wipers prior to the forward return movement of the inside form 2 and preferably also prior to the flexing of the toggle 22 to open the outer mold and thus release the upper materials from molding pressure. The machine herein shown is accordingly provided with means for depressing the hook member 70 and thus releasing the pin 69 to permit the latch 66 to return to its clutch releasing position while the toggle 22 still holds the outer mold closed upon the upper. This means comprises a pin 89 which projects over the member 70 and is carried by a bar 25 pivotally connected at its lower end to a lever arm 24 provided with a roll which lies in a cam groove suitably formed to operate the pin 89 at the required time. When the member 70 is depressed to release the latch 66, the latter immediately drops down to its clutch releasing position and the wipers are then disconnected from their operating means and are stopped in retracted position as in the construction shown in prior Patent No. 1,197,439. Subsequently the outside mold and the inside former are operated to release the work and the pin 89 is raised to permit the member 70 to resume its operative relation to the pin 69 upon the return of the toggle 22 to its starting position.

The method herein disclosed of shaping shoe upper materials is not claimed in this application but in a copending application, Serial No. 232,917, filed on May 6, 1918.

Having thus described my invention, what

I claim as new and desire to secure by Letters Patent of the United States is:

1. In an upper shaping machine, the combination with a form, and wipers adapted to bend the marginal portion of the upper inwardly over the margin of the bottom face of said form, of means constructed and arranged to engage the marginal portion of the upper inbent by said wipers and in co-operation with the wipers to shape said marginal portion with a flange upstanding from the bottom face of said form at a substantially definite angle thereto and located a predetermined distance inwardly from the edge of said face around the end and along the sides of the form.
2. In an upper shaping machine, the combination with a shoe end form and end embracing wipers adapted to gather and bend the marginal portion of the upper inwardly over the margin of the bottom face of said form, of means constructed and arranged to present a molding face extending around the end of the form for engagement with the margin of the upper opposite to the edges of the wipers to shape the upper with a sewing flange outstanding from the bottom face of said form at a predetermined angle to said face and located a predetermined distance inwardly from the edge of said face.
3. In a machine for shaping the end of a shoe upper, the combination with a shoe end form and end wipers adapted to bend the upstanding marginal portion of the upper inwardly over the margin of the bottom face of said form, of means mounted on said face of the form opposite to the edges of said wipers and constructed to co-operate with the wipers as the latter bend the upper over the margin of said face to shape the margin of the upper with a sewing flange upstanding from the bottom face of the form at a definite angle to said face and located at a predetermined distance inwardly from the edge of said face around the end of the form.
4. In a machine for shaping the end of a shoe upper, the combination with a shoe end form and end wipers adapted to bend the upstanding marginal portion of the upper inwardly over the margin of the bottom face of said form, of a flange forming member of permanent contour constructed and arranged to maintain the upper against the end wipers as they advance over the margin of said face and in co-operation with said wipers to shape the edge of the marginal portion of the upper into a flange upstanding from said face at a definite angle relatively thereto.
5. In a machine for shaping the end of a shoe upper, the combination with a shoe end form and end wipers adapted to bend

the upstanding marginal portion of the upper inwardly over the margin of the bottom face of the form, of a flange forming member of permanent contour guided for movement longitudinally of said form and constructed and arranged to maintain the upper against the advancing wipers for a determinate distance inwardly from the edge of said form face and in co-operation with the wipers, to shape the edge portion of the margin of the upper into a flange upstanding at a definite angle to the bottom face of the form and located a determinate distance inwardly from the edge of said face.

6. In a machine for shaping the end of a shoe upper, the combination with a shoe end form and end wipers arranged to advance over the margin of the bottom face of the form to bend the marginal portion of the upper inwardly over the edge of said form face, of a flange forming member of permanent contour guided on said form for movement longitudinally thereof and presenting a flange forming edge face extending at a definite angle to the bottom face of said form, means yieldingly projecting said member toward the end of said form to maintain the upper against the advancing wipers and permitting said member to retreat responsively to advancing movement of the wipers, and means determinately to limit said retreating movement and to position the edge of said member at a predetermined distance from the edge of said form face.

7. In a machine for shaping the end of a shoe upper, the combination with a shoe end form and end wipers adapted to bend the upstanding marginal portion of the upper inwardly over the bottom face of the form, of a flange forming member of undeformable edge contour guided for movement longitudinally of the form and presenting a flange forming edge face extending at a definite angle to the form face and movable a determinately limited distance inwardly from the edge of said face responsively to advancing movement of the wipers over the form face.

8. In a machine for shaping the end of a shoe upper, the combination with a shoe end form and end wipers adapted to bend the marginal portion of the upper over the bottom face of said form, of a flange forming member of permanent edge contour guided on said form for movement longitudinally thereof and presenting a flange forming edge face upstanding at a definite angle to the bottom face of said form, a bell crank lever having one arm arranged yieldingly to maintain said member moved toward the rear extremity of said form and movable with said member responsively to advancing movement of the wipers over the edge of said form face, and a swinging latch

disposed in the path of said responsive movement of the bell crank lever to engage and hold the other arm of said lever.

9. In an upper shaping machine, the combination with a shoe end form and end wipers adapted to advance over the bottom face of the form to bend the margin of the upper materials inwardly over the face of the form to produce a flange parallel to said face, of means located inwardly from the edge of said form face and arranged to hold the margin of the upper materials against the advancing wipers and, in co-operation with said wipers, to shape the edge of the marginal portion of said materials into a second flange upstanding from the form face at a definite angle to said face and to the first flanged portion of said materials.

10. In an upper shaping machine, the combination with a shoe end form and end wipers adapted to be advanced over the bottom face of the form to bend the margin of the upper inwardly over the face of the form, of margin holding means of permanent undeformable edge contour mounted on and guided by the form for movement relatively thereto responsive to advancing movement of the wipers and effective to hold the margin of the work against the advancing wipers.

11. In an upper shaping machine, the combination with a shoe end form and means adapted to bend the margin of a shoe upper inwardly over the bottom face of said end form, of margin holding means guided on the form for movement longitudinally thereof, means effective to move said margin holding means to a normal position adjacent to the edge of the end of the form, and means adjustable to vary the position to which said margin holding means is normally moved.

12. In an upper shaping machine, the combination with a shoe end form, and end wipers adapted to bend the margin of the shoe upper over the bottom face of said form, of a margin holding block of permanent edge contour guided on said form for movement longitudinally thereof and having a flange forming end face upstanding at a definite angle to said form face, means effective yieldingly to press said block into a position adjacent to the edge of said form, and means adjustable to vary the position to which said block is pressed.

13. In a machine of the class described, end embracing wipers comprising end wiper plates and side wiper plates, controlling means for the side wiper plates constructed to restrain them substantially from movement lengthwise of the shoe during their operation on the shoe while permitting them to be closed inward laterally of the shoe, and means for imparting closing

movement to said end and side plates and for imparting to the end plates a proportional advancing movement along the side plates including mechanism adjustable to vary the limit of operative movement of the several plates, the side plates also being adjustable lengthwise of the shoe relatively to the end plates.

14. In a machine of the class described, end embracing wipers comprising end wiper plates and side wiper plates, controlling means for the side wiper plates constructed to restrain them substantially from advancing movement during their operation on a shoe while permitting them to be closed inward laterally of the shoe, means for advancing the end plates along the side plates, and mechanism for causing said end and side plates to be closed inward proportionally to said advancing movement of the end plates, said mechanism being adjustable to vary the limit of said closing movement and connected to said controlling means for the side plates to effect a proportional lengthwise adjustment of the side plates.

15. In a machine of the class described, end embracing wipers comprising end wiper plates and side wiper plates, means for advancing said end wiper plates, wedge mechanism constructed and arranged to cause said end and side plates to be swung inward laterally of the shoe proportionally to the advancing movement of the end plates, and connections between said wedge mechanism and the side plates to restrain them substantially from advancing movement, said mechanism and connections being adjustable to vary the limit of closing movement of the several plates and to adjust the side plates proportionally lengthwise of the shoe.

16. In a machine of the class described, end embracing wipers comprising end wiper plates having wiping edges curved for engagement with the upper around the end of a shoe and side wiper plates having formed wiping edges arranged to serve as continuations of the regular contour of the edges of the end plates when the wipers are closed, controlling means constructed to restrain the side plates substantially from movement lengthwise of the shoe during their operative movement while permitting them to be closed inward laterally of the shoe, and means for effecting lateral closing movement of said end and side plates and for proportionally advancing the end plates along the side plates to a point where the formed edges of the end plates substantially join the formed edges of the side plates including mechanism adjustable to vary the limit of said operative movement of the several plates, said controlling means for the side plates being movable with said

mechanism to effect a compensating adjustment of the side plates to insure continuity of the regular edges of the end and side plates under the changed conditions.

- 5 17. In a machine of the class described, end embracing wipers comprising wiper carriers, end wiper plates fast on said carriers, side wiper plates mounted slidably upon the carriers, means for imparting advancing 10 movement to said carriers, means comprising slots in said carriers and normally stationary pins in said slots to cause the carriers to close the end and side plates inward laterally of the shoe in proportion to the 15 advancing movement of the carriers, said pins being adjustable to vary the limit of closing movement of the wiper plates, and links connecting said pins to the side wiper plates to restrain them substantially from 20 advancing movement with the end plates, said links being movable with the pins to effect a compensating adjustment of the side plates when the limit of movement of the wipers is varied.
- 25 18. In a machine of the class described, end embracing wipers comprising end wiper plates and side wiper plates, means for imparting a closing movement laterally of the shoe to said end and side plates and 30 a proportional advancing movement to the end plates, and means comprising pivoted links connected to the side plates to restrain them substantially from advancing movement while permitting them to be 35 closed in laterally of the shoe, said links being movable to adjust the side plates lengthwise of the shoe.
- 40 19. In a machine for shaping an end portion of a shoe upper, an inside form, an outer mold for shaping the upper to the sides of the form, shaping wipers for bending the margin of the upper over the face of the form, means for relatively moving the mold and form to seat the form in the 45 mold, operating means for closing the mold on the form to shape the upper, power operated mechanism for the shaping wipers including a clutch controlling member, and means to operate said member to start the 50 wipers through operation of the mold closing means.
- 55 20. In a machine for shaping an end portion of a shoe upper, an inside form, an outer mold for shaping the upper to the sides of the form, shaping wipers for bending the margin of the upper over the face of the form, means for relatively moving the mold and form to seat the form in the mold and subsequently to retract the form, operating means for closing and opening the 60 mold on the form, power operated mechanism for the shaping wipers including a clutch controlling member, connections from said mold operating means to said controlling member effective to cause said mem-

ber to start the wipers responsively to mold closing actuations of said operating means, and means for retracting the wipers prior to retraction of the form.

21. In a machine for shaping an end portion of a shoe upper, an inside form, an outer mold for shaping the upper to the sides of the form, shaping wipers for bending the margin of the upper over the face of the form, means for relatively moving the mold and form to seat the form in the mold and subsequently to retract the form, power operated means for actuating the wipers including a clutch controlling member movable to start and stop the wipers, power operated means for closing and opening the mold, connections between said mold operating means and said clutch controlling member effective automatically to cause said member to start the wipers when the mold 85 is closed, and means operated in time relation to the opening of the mold to retract the wipers prior to the retraction of the form.

22. In an upper shaping machine, a shoe 90 end form, a substantially U-shaped outer mold to embrace the form, yielding pressure applying members at the rear end, corners and sides of the mold including wedge members adjacent to the extremities of the sides 95 of the mold, and means for forcing said pressure members against the mold including thrust rolls acting against said wedge members.

23. A machine for shaping the heel ends 100 of shoe uppers having a heel end form, a substantially U-shaped outer mold to embrace said form, pressure applying members at the end, corners and sides of the mold including yielding wedge members at the 105 forward shank embracing ends of the mold provided with thrust receiving surfaces, and means to force said pressure members against the mold.

24. In an upper shaping machine, a shoe 110 end form, a substantially U-shaped outer mold to embrace the form, means for applying closing pressure to said mold at the end, corners and sides including yielding pressure applying members at the forward 115 ends of the mold having thrust receiving surfaces and thrust members operating in wedging engagement with said surfaces, and means positively to retract the end portions of the mold.

25. In a machine for shaping an upper over a shoe form, upper shaping means movable inwardly over the bottom face of said form in engagement with the outer surface of the margin of the upper to bend the 125 margin inwardly over said face, an upper flanging device movable inwardly with said upper shaping means in engagement with the inner surface of the margin of the upper, and means for limiting the inward 130

movement of said device to cause the inner portion of the margin of the upper to be shaped between said device and shaping means to produce a flange extending at an 5 angle to the bottom face of the form.

26. In a machine for shaping an upper over a shoe form, upper shaping means movable inwardly over the bottom face of said form in engagement with the outer 10 surface of the margin of the upper to bend the margin inwardly over said face, an upper flanging device movable inwardly with said upper shaping means in engagement with the inner surface of the margin of 15 the upper, means for limiting the inward movement of said device to cause the inner portion of the margin of the upper to be shaped between said device and shaping means to produce a flange extending at an 20 angle to the bottom face of the form, and means for preventing outward return movement of said device during return movement of said shaping means.

27. In a machine of the class described, 25 the combination with a shoe form, of end embracing wipers movable to gather and wipe the margin of an upper inwardly over the bottom face of said form, a flanging device arranged to engage the inner surface 30 of the margin of the upper and to be moved inwardly over the form by the pressure of the wipers, and means for limiting the inward movement of said device to cause the inner portion of the margin of the upper to be 35 shaped between said device and the wipers to produce a flange extending at an angle to the bottom face of the form.

28. In a machine of the class described, the combination with a shoe form, of end 40 embracing wipers movable to wipe the margin of an upper inwardly over the bottom face of said form, means automatically operative to impart to said wipers a series of reciprocatory movements, a flanging device arranged to engage the inner surface 45 of the margin of the upper and to be moved inwardly over the form by the first advance of the wipers, means for opposing yielding resistance to said movement of the flanging 50 device, means for limiting the inward movement of said device to cause the inner portion of the margin of the upper to be shaped between said device and the wipers to produce a flange extending at an angle to the 55 bottom face of the form, and means for preventing outward return movement of said device during subsequent movements of the wipers.

29. In a machine of the class described, 60 the combination with a shoe form, of means for wiping the margin of an upper inwardly over the bottom face of said form, a flanging device movable inwardly over said face in response to the pressure of the wipers, 65 and means for limiting the inward move-

ment of said device to position its outer edge at a distance from the edge of the bottom face of the form less than the width of the margin of the upper projecting beyond said face to serve as an abutment against which 70 to shape the margin of the upper into an upstanding flange.

30. In a machine for shaping the end portion of a shoe upper, a shoe form having a guideway extending along its bottom face, 75 a flanging plate mounted for movement along said guideway, end embracing wipers constructed and arranged to wipe the margin of the upper inwardly over said form and to force said plate along its guideway, 80 and means for limiting the movement of said plate to cause the margin of the upper to be shaped between said plate and the wipers to produce a flange extending at an angle to the bottom face of the form. 85

31. In a machine of the class described, the combination with inner and outer forming members relatively movable into operative relation to the end portion of the upper of a shoe, of end embracing wipers, power 90 means for operating said wipers, and controlling means constructed and arranged to cause the operation of said wipers to be started by the relative movement of said forming members to operative position. 95

32. In a machine of the class described, a shoe end embracing band, means for closing said band about the end of a shoe, end embracing wipers, power means for operating said wipers, wiper controlling mechanism, 100 and connections between said mechanism and the band closing means to cause the wipers to be started in operation by the closing of the band.

33. In a machine of the class described, 105 the combination with shoe end embracing and clamping means, of a member movable lengthwise of the shoe to operate said means, end embracing wipers, power means including a clutch for operating said wipers, and mechanism connected to said lengthwise movable member for actuating said clutch. 110

34. In a machine of the class described, the combination with inner and outer forming members relatively movable into operative relation to the end portion of the upper of a shoe, of operating means for effecting relative movement of said members, end embracing wipers, power means for operating said wipers, means for starting the operation 115 of the wipers by the relative movement of said members to operative position, and additional means constructed and arranged to stop the operation of the wipers independently of the relative reverse movement of 120 said members.

35. In a machine of the class described, a shoe end embracing band, means for closing said band about the end of a shoe, end embracing wipers, power means including a 130

clutch for operating said wipers, mechanism connected to said band closing means for actuating said clutch, and means for rendering said mechanism effective to stop the operation of the wipers independently of the opening of the band.

36. In a machine of the class described, shoe clamping means comprising wedge members pivoted respectively at opposite 10 sides of a shoe to swing laterally of the shoe, and means movable lengthwise of the shoe along said members to force them inwardly toward the shoe.

37. In a machine of the class described, 15 the combination with a shoe end embracing and clamping member, of operating members supported on the opposite sides of said clamping member, yieldable pressure applying means between said operating members 20 and the clamping member, and means movable in wedging engagement with said operating members to force them inwardly toward the shoe.

38. In a machine of the class described, 25 the combination with a shoe end embracing band, of pressure applying members pivoted respectively at opposite sides of said band, yieldable pressure applying means between said pressure applying members and the 30 band, and means movable lengthwise of the shoe in wedging engagement with said members to force them inwardly toward the shoe.

39. In a machine of the class described, 35 the combination with a shoe end embracing band, of means for closing the band inwardly against the sides of the shoe including yieldable pressure applying devices at opposite sides of the band, and additional positive connections to the band for opening it.

40. In a machine of the class described, 40 the combination with a shoe end embracing band, of wedge mechanism movable lengthwise of the shoe to force said band against the shoe, and additional means connected to 45 the band and arranged to be operated by the

reverse movement of said mechanism to open the band.

41. In a machine of the class described, the combination with a shoe end embracing band, of wedge members yieldingly connected respectively to the opposite sides of said band, operating means movable lengthwise of the shoe in wedging engagement with said members for closing the band on the 50 shoe, and additional means connected to the band and arranged to be operated by the reverse movement of said operating means to open the band.

42. In an upper shaping machine, the 60 combination with outer shaping means constructed and arranged to gather and bend the margin of upper materials inwardly around the end of a shoe, of coöperating inner shaping means constructed to present a 65 marginal face substantially parallel to the plane of the shoe bottom over which the margin of the upper is to be bent by said outer shaping means and a face transverse to said marginal face and extending around 70 the end of the shoe from one side to the other at a determinate distance from the outer edge of said marginal face for engagement with the upper materials to mold them into an upstanding flange adapted to 75 be sewed to the rib of an insole.

43. In an upper shaping machine, the combination with end embracing wipers, of a shoe end form over which the margin of the upper is to be gathered and bent inwardly 80 by the wipers, and means on said form constructed to present an abutment face transverse to the plane of the wipers and extending around the end of the form at a determinate distance from the outer edge of the 85 form for engagement with the margin of the upper materials to mold them into an upstanding flange adapted to be sewed to the rib of an insole.

In testimony whereof I have signed my 90 name to this specification.

MATTHIAS BROCK.
